NONCORROSIVE DETERGENT
COMPOSITIONS

Jay C. Hurris, Dayton, Ohio, assignor to Monsanto Chemical Company, St. Louis, Mo., a corporation of Delaware

No Drawing. Application November 25, 1949,
Serial No. 129,539

7 Claims. (Cl. 252—140)

1

This invention relates to detergent compositions suitable for washing textiles and for other purposes. It relates particularly to detergent compositions which may be used in automatic washing machines which are constructed in whole or in part of vitreous enameled metal or of aluminum.

This application is a continuation-in-part of my copending application Serial No. 61,738, filed November 23, 1948, and now abandoned.

In an earlier copending application, Serial No. 637,096, filed December 22, 1945, now abandoned, which application is assigned to the same assignee as is the present case, there is disclosed the condensation product of tall oil with ethylene oxide, said condensation products containing at least 0.5 part, but less than 2.3 parts of ethylene oxide per part of tall oil. There is also disclosed in the same application a combination of the said condensation products with alkaline builders, such as the sodium phosphates, particularly tetrasodium pyrophosphate, soda ash, starch, etc. The compositions so produced are highly efficient detergents.

I have now found that when such compositions as above disclosed are employed in automatic laundry machinery, such as household washing machines, constructed in whole or in part of aluminum or of vitreous enameled steel, the surfaces of these devices in contact with detergent solutions are etched or corroded so as to lead to an undesirable roughening of the surfaces so exposed, and in some cases to failure of the vitreous coating.

I have also discovered that substantially complete protection of such surfaces can be obtained by including in the detergent compositions from 6% to 25% by weight, based upon the combined weight of phosphates and carbonates of a soluble sodium silicate, wherein the $\text{Na}_2\text{O}:\text{SiO}_2$ mole ratio is between 1:2 to 1:3.2. The percentage of the silicate stated above is based upon the anhydrous form. Any water soluble form of sodium silicate may be employed. The phosphates and carbonates in the composition may be in the hydrated or anhydrous form; however, when in the hydrated form allowance should be made for the amount of water present in order to maintain the ingredients when dissolved in water within the effective range of proportions disclosed and

claimed. The percentage of sodium silicate is therefore based upon the anhydrous phosphates and carbonates present in the composition. Soluble silicates may be in solid form or they may be employed in aqueous solutions, which solutions may contain up to 85% of water.

The present composition also contains tetrasodium pyrophosphate or the sodium tripolyphosphate, $\text{Na}_5\text{P}_3\text{O}_{10}$, either in anhydrous or hydrated form. Perfumes such as "Citropene" may be added if desired.

The constitution of the sodium silicates employed should be maintained within the limits stated so that the silicates will dissolve in the detergent solution at a rate sufficiently rapid so that they will be effective for corrosion prevention from the instant of solution of the detergent. They should, moreover, be employed in the amount stated above, since I have found that quantities below the lower limit given are ineffective for the purpose, while quantities above the upper limit are undesirable because of an adverse effect upon the detergent efficiency of the composition.

The preferred proportions of the ingredients in the present product, together with the range of ingredients effective for the present purpose, are as follows, all parts being by weight:

	Parts
30 Condensation product of tall oil with ethylene oxide in the ratio of 0.5:2.3 per part of tall oil	10-25
35 Tetrasodium pyrophosphate, sodium tripolyphosphate, or mixtures thereof (anhydrous basis)	20-60
30 Sodium silicate, $\text{Na}_2\text{O}:\text{SiO}_2$ ratio of 1:2 to 1:3.2 (anhydrous basis)	6-25
35 Starch	0-20
40 Alkaline material selected from the class consisting of sodium carbonate, sodium bicarbonate and mixtures thereof (anhydrous basis)	10-25

To the above product may be added from 0.1 to 5 parts of carboxy methyl cellulose.

For washing soiled textiles, the above compositions are dissolved in hot water to give preferably a 0.1% to 0.25% by weight solution, although other concentrations may also be employed.

The following more specific examples illustrate the invention:

EXAMPLE 1

A composition consisting of an intimate mixture of the following ingredients is prepared, the proportions being based on the anhydrous salts.

	Parts
Condensation product of one part of tall oil with 1.6 parts of ethylene oxide	15.00
Tetrasodium pyrophosphate	40.00
Soda ash	20.25
Solid sodium silicate ("G" Silicate) Na ₂ O:SiO ₂ =1:2	24.00
Carboxy methyl cellulose	0.75
 Total	 100.00

The above composition was prepared by adding the tall oil-ethylene oxide condensation product in liquid form to finely powdered tetrasodium pyrophosphate in a mixing device and then adding the soda ash, the sodium silicate and carboxy methyl cellulose. The order of addition is not critical and the ingredients stated may be added in any desired order.

EXAMPLE 2

	Parts
Condensation product of one part of tall oil with 1.8 parts of ethylene oxide	20
Sodium tripolyphosphate	40
Sodium carbonate	15
Sodium silicate (anhydrous) Na ₂ O:SiO ₂ =1:3.2	10
Starch	14
Carboxy methyl cellulose	1
 Total	 100

EXAMPLE 3

	Parts
Condensation product of one part of tall oil with 1.6 parts of ethylene oxide	15.00
Tetrasodium pyrophosphate (anhydrous basis)	40.00
Soda ash	20.15
Sodium silicate solution (water glass, 38% solids, 62% water) Na ₂ O:SiO ₂ =1:3.2	24.00
Carboxy methyl cellulose	0.75
Perfume (Citropene)	0.10
 Total	 100.00

The above compositions provide excellent detergency without noticeable action on vitreous enamel or aluminum washer baskets.

The composition presented in Example 3 above may be formed by mixing the condensation product with the finely ground tetrasodium pyrophosphate and soda ash, then adding the liquid sodium silicate, followed by the remaining ingredients. The water contained in the silicate solution will hydrate the anhydrous salts forming hydrated salts. The quantity of water glass employed (24 parts), since it contains about 62% of water, will furnish sufficient water to hydrate the soda ash to the sodium carbonate monohydrate, and somewhat less than half of the tetrasodium pyrophosphate to the decahydrate. This composition, therefore, contains 15% by weight of water of hydration. Additional water may be added if desired in order to more completely hydrate the salts. By so hydrating the salts either partly or completely in the presence of the condensation product a better retention of the oily condensation product is obtained. This is more

fully described and claimed in copending application to Louis E. Wells and Henry V. Moss, Serial No. 92,954, filed May 12, 1949, which application is assigned to the same assignee as is the present case.

When water is added to the composition either in the form of an aqueous silicate solution or as such, it may be added in amount sufficient to hydrate the tetrasodium pyrophosphate at least to an average of 3.5 moles of water, but not in excess of 10 moles of water per mole of tetrasodium pyrophosphate. A range of from 3.5 moles to 5 moles of water is preferred in practice. When sodium tripolyphosphate is employed in the composition, from 3 to 6 moles of water may be employed, the lower limit (3 moles) per mole of sodium tripolyphosphate being preferred. Soda ash is advantageously hydrated to the monohydrate, whereas sodium sesquicarbonate is hydrated to 2 moles of water per mole of sesquicarbonate.

It has been found that when an amount of water equivalent to 10 moles of water per mole of tetrasodium pyrophosphate is employed the initially formed product is quite damp. However, upon aging for several days at room temperature a satisfactory dry product is obtained.

The amount of sodium silicate employed should be from 6 to 25 parts per 20 to 60 parts of phosphate and 10 to 25 parts of the carbonate reckoned on the anhydrous basis. By employing these proportions excellent detergency is obtained without encountering corrosion of vitreous enameled or aluminum surfaces. Within these limits the product does not absorb excessive amounts of moisture from humid air under conditions ordinarily encountered in the use of the detergent. The detergent remains free-flowing, exhibiting no tendency to cake due to the silicate present.

Corrosion tests made by exposing weighed pieces of aluminum metal of the same area (49.9 sq. cm.) to 0.25% aqueous solutions of various detergent compositions at a temperature of 140° F., gave the following weight losses in duplicate tests. Each exposure was for 10 minutes and a total of 10 exposures were made before final weighing.

50	Product Tested	Grams Loss in Weight
1		0.0107 and 0.0112
2		0.0041 and 0.0047
3		0.0071 and 0.0066
4		0.0018 and 0.0015

Composition of product tested, parts by weight

60	1	2	3	4
Tall oil—ethylene oxide condensation product	20.0	15.0	15.0	15.0
Tetrasodium pyrophosphate	40.0	40.0	40.0	40.0
Starch	19.25	8.25	4.0	
Soda ash	20.25	20.25	20.25	20.25
Sodium silicate (62% H ₂ O), ratio Na ₂ O:SiO ₂ =1:3.2	24.0	15.75	20.0	
Sodium sesquicarbonate	20	0.75	0.75	0.75
Carboxy methyl cellulose	0.75	0.75	0.75	0.75

The hydration reaction taking place when aqueous sodium silicates are employed may evolve a considerable amount of heat, particularly when the freshly prepared composition is allowed to stand in large piles. This results in a lumpy product. It is desirable, therefore, that the 70 freshly mixed composition be stored in relatively

shallow piles or layers which are on the order of one foot in thickness. Alternatively the mixed material may be placed upon a moving belt in a layer several inches thick, which layer is then caused to be discharged upon another moving belt until such time as the hydration reaction has been completed and then into suitable storage receptacles. When this has occurred the material is a non-caking and free-flowing powder.

What I claim is:

1. A detergent composition comprising the following essential ingredients in parts by weight:

Condensation product of tall oil with ethylene oxide containing from 0.5 part to 2.3 parts of ethylene oxide per part of tall oil

10-25

A phosphate material selected from the group consisting of tetrasodium pyrophosphate and sodium tripolyphosphate (anhydrous basis)

20-60

Alkaline material selected from the group consisting of sodium carbonate, sodium bicarbonate and mixtures thereof (anhydrous basis)

10-25

said composition containing in addition from 6% to 25% by weight, based on the combined weight of said phosphate material and said alkaline material, of a sodium silicate having an

$\text{Na}_2\text{O}:\text{SiO}_2$

ratio of from 1:2 to 1:3.2.

2. A detergent composition comprising the following essential ingredients:

Condensation product of tall oil with ethylene oxide containing from 0.5 part to 2.3 parts of ethylene oxide per part of tall oil

10-25

A sodium phosphate selected from the group consisting of $\text{Na}_4\text{P}_2\text{O}_7$ and

$\text{Na}_5\text{P}_3\text{O}_{10}$

(anhydrous basis)

20-60

Sodium silicate $\text{Na}_2\text{O}:\text{SiO}_2$ ratio from 1:2 to 1:3.2 (anhydrous basis)

6-25

Alkaline material selected from the group consisting of sodium carbonate, sodium bicarbonate and mixtures thereof (anhydrous basis)

10-25

3. A detergent composition comprising the following essential ingredients:

Condensation product of one part of tall oil with 1.6 parts of ethylene oxide

20.00

Tetrasodium pyrophosphate

40.00

Soda ash

20.15

Solid sodium silicate, $\text{Na}_2\text{O}:\text{SiO}_2=1:2$

15.00

Carboxy methyl cellulose

0.75

4. A detergent composition comprising the following essential ingredients:

Parts

Condensation product of one part of tall oil with 1.6 parts of ethylene oxide

15.00

Sodium tripolyphosphate (anhydrous basis)

40.00

Sodium carbonate

20.15

Sodium silicate (anhydrous basis)

24.00

$\text{Na}_2\text{O}:\text{SiO}_2=1:3.2$

24.00

Carboxy methyl cellulose

0.75

5. A detergent composition comprising the following essential ingredients:

Parts

Condensation product of one part of tall oil with 1.4 parts of ethylene oxide

20

Tetrasodium pyrophosphate (anhydrous basis)

40

Sodium sesquicarbonate (hydrated basis)

18

Sodium silicate (anhydrous) $\text{Na}_2\text{O}:\text{SiO}_2=1:2$

20

Carboxy methyl cellulose

2

6. The process which comprises dissolving in water a detergent product having a composition as defined by claim 1 to form a detergent solution and then washing textiles therewith, said washing process being conducted in the presence of vitreous enameled or aluminum surfaces, whereby corrosion of said surfaces normally occurring in the absence of the sodium silicate contained in said product is substantially prevented.

7. The process which comprises dissolving in water a detergent product having a composition as defined by claim 2 to form a detergent solution and then washing textile products therewith, said washing process being conducted in the presence of vitreous enameled or aluminum surfaces, whereby corrosion of said surfaces normally occurring in the absence of the sodium silicate contained in said product is substantially prevented.
